UNITED STATES PATENT OFFICE.

MOIS H. AYRAM, OF NEW YORK, N. Y., ASSIGNEE TO SLOCUM, AYRAM & SLOCUM, INC.,
OF NEW YORK, N. Y.

AUTOMATIC TIME-SWITCH.

1,151,848.

Specification of Letters Patent. Patented Aug. 31, 1915.

Application filed July 8, 1914. Serial No. 349,652.

To all whom it may concern:

Be it known that I, Mois H. AYRAM, a citizen of the United States, residing at New York city, county and State of New York, have invented certain new and useful Improvements in Automatic Time-Switches, of which the following is a specification.

This invention relates to a novel automatic time switch which is more particularly designed to be used in conjunction with an efficiency recorder for machines, etc., such as for instance shown and described in a pending patent application filed by me January 28, 1914, under Serial Number 813,850. I have found it to be of the utmost importance with respect to a reliable operation of such a recorder, that the electric contact which is repeatedly closed by the machine to be controlled, be maintained for a certain length of time. In this way only, a proper energizing of the electromagnets that form part of the efficiency recorder, is obtained.

My improved switch contains further novel and effective means for maintaining a signal at a point distant from the machine, for indicating that the latter is in operation.

In the accompanying drawing: Figure 1 is a face view partly broken away of my improved time switch with the casing open; Fig. 2 a cross section on line 2—2, Fig. 1, with some of the parts omitted; Fig. 3 a longitudinal section through the air cylinder and coöperating parts; Fig. 4 a detail of the signaling lamp-operating means; Fig. 5 an enlarged cross section, on line 5—5, Fig. 4; Fig. 6 a wiring diagram of the recording circuit; and Fig. 7 a wiring diagram of the signaling circuit.

Through suitable dust-tight stuffing boxes 10, 11 of a casing 12 passes a reciprocating rod 13 the eye 14 of which is adapted to be coupled in suitable manner to a movable part of the machine to be controlled. Rod 13 is straddled by a feed lever 15 which is loosely mounted on a boss 12 of casing 12 said boss supporting a stud 16. Intermediate the bushing 10 and lever 15 is arranged a pressure spring 17, while between a relatively fixed collar 18 of rod 13 and lever 15 there is interposed a spring 19, both of the springs 17 and 19 encircling rod 13. The tension of the springs 17 and 19 should be such that when the switch is at rest, lever 15 abuts against a fixed pin 20. To lever 15 is pivoted at 21 a feed pawl 22

influenced by a spring 23 and engaging the teeth of a ratchet wheel 24 loosely mounted on stud 16. Ratchet wheel 24 is further engaged by a detent 25 pivoted at 26 to casing 12 and influenced by a spring 27. Opposite wheel 24 and spaced therefrom is arranged a disk 28, the drawing showing the parts 24, 28 to be made integral with a common hub 29. Wheel 24 is provided with a plurality of sockets 30 arranged in a circle, while disk 28 is furnished with a like number of similarly disposed perforations 31. Into each pair of aligned sockets 30 and perforations 31 is adapted to be fitted a pin 32. These pins are prevented from displacement by a plate 33 abutting against disk 28 and thereby closing perforations 31, the plate 33 being held in position by a cotter 34.

Pins 32 are adapted to be engaged by the tapering nose 35 of a lever 36 pivoted at 37 to casing 12 and influenced by a spring 38. Near its free end, lever 36 engages the slot 39 of a piston 40, to which slot the lever is confined by a transverse pin 41. Piston 40 is snugly fitted into a stationary cylinder 42, the inward movement of the piston being limited by a collar 43 adapted to abut against said cylinder. Into the latter is further fitted a freely movable plunger 44, the outward play of which is restricted by a cap 45 screwed on the cylinder. The opposed inner faces of piston 40 and plunger 44 are concaved as at 46, 47 respectively to form air pockets. Plunger 44 is provided with an annular recess 48 for the accommodation of a spring 49 that tends to force the plunger inward. The latter has further an axially extending stem 50 that projects outward through a corresponding perforation of cap 45 while a pin 50^a limits the inward play of plunger 44. Stem 50 engages a first contact spring 51 arranged opposite a second contact spring 52 and spaced therefrom, the springs 51, 52 being shown to be secured to a common block 53 of insulating material. Spring 51 is connected to a source of electricity 54 by a wire 55, while spring 52 is connected through wire 56 to an electromagnet A, said electromagnet corresponding to the electromagnet 57 referred to in the above identified patent application. Electromagnet A is connected with source 54 through wire 57.

As thus far described the operation is as follows: During each reciprocation of rod 13, lever 15 moves once back and forth,

therby advancing ratchet wheel 24 for one tooth. As the number of sockets 30 and perforations 31 equals that of the teeth of ratchet wheel 24 and as furthermore each of the pairs of aligned sockets and perforations is in Fig. 1 shown to be provided with a pin 32, it is obvious that during each reciprocation of lever 15, lever 36 will also perform a complete reciprocation. During the advance of the pin 32, lever 36 will first be gradually forced outward to correspondingly withdraw plunger 40 from cylinder 42, the clearance between said cylinder and piston 40 and plunger 46 being so calculated as to admit sufficient air into the chamber 58 formed between the parts 40, 44 without creating a vacuum therein. As soon as the pin 32 clears nose 35 of lever 36, spring 38 will retract said lever and thus return piston 40 to its original position. Owing to the volume of air entrapped between piston 40 and plunger 44, the sudden return of said piston will throw the plunger outward against the action of spring 49, the outward movement of said plunger being so calculated that the stem 50 not only brings spring 51 into contact with spring 52 but bends both of said springs slightly outward to produce a frictional or sliding movement therebetween. As a certain time is required before spring 49 can return plunger 44 to its original position owing to the time required for the entrapped air to escape, it is obvious that a contact is maintained between the contact springs 51, 52 for almost the same length of time. In this way the circuit 54, 57, A, 56, 52, 51, 55, 54 is maintained closed for a period sufficiently long to warrant under all circumstances the proper energizing of electromagnet A necessary for a reliable operation of the recording device. It will further be seen that it is impossible with this device that the circuit remains closed for any protracted length of time after having performed its work, irrespective of the position in which the machine controlled by the efficiency recorder happens to come to a stop. In case the movable member of said machine to which rod 13 is connected, has a high speed, or if a less frequent operation of the recording device is desired, alternating pins 32 or more of such pins may be removed from wheel 24, 28, the slowest operation being of course obtained if but one pin 32 is carried by said wheel. This removal and reinsertion of pins may be readily effected by withdrawing cotter 34 and plate 33 whereby the perforations 31 and pins 32 are rendered readily accessible.

In order to indicate at a distant point as to whether the machine to which the above described time switch is connected, is running or not, the following construction has been devised: Lever 15 is provided with an

extension 59 that carries a pair of sector-shaped racks 60, 61. Of these, rack 60 engages a pinion 62 while rack 61 engages a similar pinion 63. Pinions 62, 63 are loosely mounted on a spindle 64 and are provided with spring-influenced pawls 65, 66 that engage ratchet wheels 67, 68 respectively, the latter being fast on spindle 64. This spindle carries further a fixed beveled gear wheel 69 meshing into a similar wheel 70 fast on a rotary spindle 71 that carries a centrifugal governor 72. This governor has a relatively fixed sleeve 73 and a movable sleeve 74 which carries a disk 75. The latter is adapted to engage an insulator 76 carried by a spring contact 77 which latter is in turn adapted to engage another spring contact 78, both of said contacts being secured to a common insulator 79. Contact 77 is, by wire 80, connected to a source of electricity 81. From the latter leads a wire 82 to a signal such as a lamp 83 which is in turn connected to contact 78 by wire 84. It will be seen that as long as rod 13 is reciprocated such reciprocation will cause governor 72 and disk 75 to be rotated, the balls of said governor and the disk acting as a fly wheel to maintain rotation irrespective of the momentary stops of racks 60, 61 at their points of reversal. Owing to this rotation, disk 75 will be lowered to effect a contact between the parts 77, 78 and to close the signal circuit. In case the machine controlled stops, disk 75 will be raised to cause a disengagement between contacts 77, 78 and thereby open the signal circuit, which opening does not depend upon the position in which the machine happens to come to a subsequent standstill.

I claim:

1. A device of the character described, comprising a reciprocal member, a cylinder, a piston slidably engaging one end of said cylinder, adjustable means for operatively connecting said member to said piston, a spring-influenced plunger slidably engaging the other end of the cylinder, and a pair of contacts adapted to be closed by said plunger.

2. A device of the character described, comprising a reciprocal rod, a feed lever actuated thereby, a pawl carried by said lever, a ratchet wheel engaged by the pawl, a plurality of removable pins carried by the ratchet wheel, a spring-influenced lever operated by said pins, and a contact making and breaking device controlled by said last named lever.

3. A device of the character described, comprising a reciprocal rod, a feed lever actuated thereby, a pawl carried by said lever, a ratchet wheel engaged by the pawl and provided with a plurality of sockets, pins removably fitted into said sockets, a spring-influenced lever operated by said

pins, and a contact making and breaking device controlled by said last named lever.

4. A device of the character described, comprising a reciprocal member, a cylinder, a piston slidably engaging one end of said cylinder, means for operatively connecting said member to said piston, said means including a device for regulating the number of reciprocations of the piston relatively to those of the member, a spring-influenced plunger slidably engaging the other end of the cylinder and spaced from the piston to form an intervening air pocket, means for limiting the inward movement of the plunger, and a pair of contacts adapted to be closed by said plunger.

5. A device of the character described, comprising a reciprocal member, a cylinder, a piston slidably engaging one end of said cylinder, means for operatively connecting said member to said piston, said means including a device for regulating the number of reciprocations of the piston relatively to those of the member, a spring-influenced plunger slidably engaging the other end of the cylinder and spaced from the piston to form an intervening air pocket, a perforated cap on the cylinder, a stem on the plunger that projects outward through the cap-perforations, and a pair of contacts adapted to be closed by said plunger.

6. A device of the character described, comprising a reciprocal member, a cylinder, a piston slidably engaging one end of said cylinder, said piston having an inner concaved end, means for operatively connecting said member to said piston, a plunger slidably engaging the other end of the cylinder and having an inner concaved end to form an air pocket between the concaved ends of the piston and plunger, means for limiting the inward movement of the plunger, and a pair of contacts adapted to be closed by said plunger.

7. A device of the character described, comprising a reciprocal member, a cylinder, a piston slidably engaging one end of said cylinder, means for operatively connecting said member to said piston, said means including a device for regulating the number of reciprocations of the piston relatively to those of the member, a recessed plunger slidably engaging the other end of the cylinder and spaced from the piston to form an intervening air pocket, a perforated cap on the cylinder, a spring seated within the recess and engaging the cap, a stem on the plunger and projecting outward through the cap-perforation, and a pair of contact springs adapted to be closed by said stem.

8. A device of the character described, comprising a cylinder, a piston engaging one end thereof and having a slotted end and a collar that is adapted to abut against the cylinder, a lever engaging the slotted

piston-end and projecting beyond the same, a spring engaging said projecting lever portion, a recessed plunger slidably engaging the other end of the cylinder and spaced from the piston to form an intervening air pocket, a perforated cap on the cylinder, a spring seated within the recess and engaging the cap, a stem on the plunger and projecting outward through the cap-perforation, means on the stem for limiting the inward movement of the plunger, and a pair of contacts adapted to be closed by said stem.

9. A device of the character described, comprising a member adapted to be reciprocated by the machine to be controlled, means controlled by said member for intermittently closing a recording circuit, and means also controlled by said member for permanently closing a signaling circuit during the reciprocations of said reciprocal member.

10. A device of the character described, comprising a member adapted to be reciprocated by the machine to be controlled, means controlled by said member for intermittently closing a time contact of a recording circuit, and means also controlled by said member for permanently closing a signaling circuit during the reciprocations of said reciprocal member.

11. A device of the character described, comprising a member adapted to be reciprocated by the machine to be controlled, means controlled by said member for intermittently closing a time contact of a recording circuit, and means also controlled by said member for permanently closing a signaling circuit during the reciprocations of said reciprocal member and for automatically opening said circuit upon an arrest of said reciprocal member.

12. A device of the character described, comprising a reciprocal member, means controlled by said member for intermittently closing a time contact of a recording circuit, and a centrifugal regulator adapted to close a signaling circuit.

13. A time switch comprising a mechanically actuated first member, a second member adapted to be advanced by the first member and movable independently therefrom, an electric contact adapted to be closed upon an advance of said second member, means for returning the second member, and means for retarding said return movement, whereby the contact is maintained closed for a length of time.

14. A time switch comprising a mechanically actuated first member, a second member adapted to be pneumatically advanced by the first member, an electric contact adapted to be closed upon an advance of the second member, and a spring for returning said second member, the pneumatic advanc-

ing means being adapted to retard said return movement of the second member whereby the contact is maintained closed for a length of time.

- 5 15. A time switch comprising a mechanically actuated first member, a second member adapted to be pneumatically advanced by the first member, a pair of yielding contacts adapted to be closed upon an advance 10 of the second member, and a spring for re-

turning said second member, the pneumatic advancing means being adapted to retard said return movement of the second member whereby the contact is maintained closed for a length of time.
